Patrick D. Riordan, Esq., D.
Inventor

UNITED STATES PATENT OFFICE.

PATRICK D. RIORDAN, OF NEW YORK, N. Y.

DESIGN FOR A FLAG FOR IRELAND.

61,253.

Specification for Design.

Patented July 18, 1922.

Application filed July 5, 1921. Serial No. 482,605. Term of patent 14 years.

To all whom it may concern:

Be it known that I, PATRICK D. RIORDAN, M. D., a citizen of the United States of America, residing at No. 131 East 86th Street, in the borough of Manhattan, in the city, county, and State of New York, have invented a new, original, and ornamental Design for a Flag for Ireland, as set forth in the annexed specification, reference being had to the accompanying drawings, forming a part thereof.

The figure is a plan view of the flag showing my new design.

The peculiar construction of my design

brings into view thirty-two stripes representing the thirty-two counties of Ireland; also, the Irish white cross dividing the said stripes into four groups representing the four provinces of Ireland; and a green cross, surrounding the white cross, representing patriotic Ireland's age-long sufferings and present resurrection to a new life in the sisterhood of the nations.

Having fully described my new design for a flag for Ireland, I claim:

The ornamental design for a flag for Ireland as shown.

PATRICK D. RIORDAN, M. D.
